PRESS HEAD FOR STUFFING MACHINES

Original Filed Dec. 29, 1920

Inventor:

Oscar C. Schmidt,
by J. P. Verble,
his Attorney.

UNITED STATES PATENT OFFICE.

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

PRESS-HEAD FOR STUFFING MACHINES.

Original application filed December 29, 1920, Serial No. 433,792. Divided and this application filed February 13, 1923. Serial No. 618,877.

To all whom it may concern:

Be it known that I, OSCAR C. SCHMIDT, a citizen of the United States, residing in Cincinnati, in the county of Hamilton and 5
5 State of Ohio, have invented certain new and useful Improvements in Press-Heads for Stuffing Machines, of which the following is a specification.

My invention relates to press-heads for 10 stuffing mechanism employable for instance in stuffing sausage casings.

My present invention is a division of my copending application for patent on improvements in stuffing mechanism, filed in 15 the United States Patent Office December 29, 1920, Serial No. 433,792, in which latter application the press-head herein shown, described and claimed is also shown and described, my present application being a 20 continuation of my aforesaid original copending application.

In stuffing mechanism of the character of that shown, described and claimed in my aforesaid copending application, a press-head is employed, so arranged that pressure is exerted upon one side of the press-head for communicating pressure to the plastic material in the cylinder at the other side of the press-head to cause the plastic material to be exuded or pressed through suitable nozzles into sausage casings, the press-head being permitted to descend by gravity to its initial position when the filling operation has been completed, or the 35 plastic material has been pressed from the cylinder.

In mechanism of this character the press-head is operable in the cylinder which contains the plastic material, and acts directly 40 upon the plastic material, to exert pressure theron for expressing the plastic material.

In order that there may be no waste of plastic material, and in order that none of the compressed fluid, such as air or water, 45 which forms the pressing medium, shall leak past the press-head into the plastic material, which would thereby form detrimental fluid pockets or air pockets in the plastic material, or in the sausage casings, 50 or burst the sausage casings, or act detrimentally on the plastic material, and in order to provide a press-head of simple construction, I have constructed a press-head which by simple means and few parts of

simple and strong construction coat with 55 the cylinder to form a close sliding joint between the press-head and the inner surface of the cylinder during the pressing action of the press-head, sufficient relief of pressure between the press-head and the 60 inner surface of the cylinder being provided by the relief of pressure upon the press-head, to permit retraction of the press-head by gravity, when such retraction is desired and the actuating pressure upon the press- 65 head is relieved.

It is the object of my invention, further, to provide a press-head comprising relatively axially movable sections substantially telescopingly arranged and having an annular outer rabbet between them, in which an annular elastic packing tube is received, so arranged that axial movement between said sections to decrease the space between them will cause compression of said elastic 75 tube in axial direction and enlargement of the same in radial directions, to more compactly fill the annular space between the inner annular wall of said outer annular rabbet and the inner surface of the cylinder, 80 in order to form a close slide-joint between said packing and said inner surface of the cylinder; and, further, to provide said sections with annular outer flanges and the respective ends of said elastic tube with 85 inner annular flanges received within said outer annular flanges to maintain a close joint between the ends of said tube and said respective sections; and the invention will be further readily understood from 90 the following description and claim, and from the drawings in which latter:

Fig. 1 is a side elevation of a stuffing machine embodying my invention, the cylinder of the stuffing machine being partly 95 broken away for better illustration.

Fig. 2 is axial vertical section of my improved device, taken in the plane of the line 2-2 of Fig. 1, and showing the members of the press-head in extended or separated relation; and,

Fig. 3 is a similar view, showing the parts of the press-head in relatively compressed relation.

The plastic material, instanced as chopped and prepared sausage meat, or, as it is called, meat dough, exemplified at 11, is placed at 105 one side of the press-head, shown at 12, in a

cylinder 13, while pressure, preferably fluid pressure, such as compressed air or water, is employed at the other side of the press-head, for forcing the plastic material through a nozzle or nozzles, one of which is shown at 14 in a cover 15 hinged to the cylinder by a hinge 16 and clamped to the cylinder by a clamp 17. The nozzle communicates with the space in the cylinder above the press-head.

The pressure required depends in great measure upon the consistency of the meat dough or plastic material, and is at times very great.

15 I have found it desirable to provide a simple press-head employing few parts, and provided with a packing so arranged that its diameter will automatically decrease upon retraction of the press-head, and automatically increase in simple manner upon movement of the press-head in opposite direction, for forming a close joint between the press-head and the inner annular surface of the wall of the cylinder, to prevent leaking of material being pressed, or the juices thereof, and of the fluid of the pressure medium, past the press-head, or into the interior of the press-head, in which latter case the pressure of the pressure medium upon 20 the inner surface of the elastic tube would cause the press-head to stick in the cylinder and cause derangement between the parts of the press-head, while the leaking of any of the plastic material or juices thereof into 25 the interior of the press-head would cause an unsanitary condition.

The press-head in its preferred form comprises an upper section 21 and a lower section 22. One of these sections, shown as the section 22, is provided with an annular rabbet 23 for forming an inner cylinder 24 of unvarying diameter, about which an elastic tube 25 is received in the annular rabbet, for being supported by said inner cylinder 45 in such manner that the inside diameter of said tube remains constant. This tube is an elastic, compressible and extensible tube. This elastic tube is preferably of rubber or of a composition having rubber as a base.

50 The opposite section of the press-head is provided with an annular flange 26, the inner face of which is an annular cylindrical face which is arranged to be telescopingly received about the outer peripheral cylindrical face forming the inner wall of the rabbet.

55 The elastic tube is received in the annular rabbet between the flange 26, which forms a shoulder for one end of the elastic tube, and a flange 27, forming one of the end-walls of the rabbet. The annular flange 26 is provided with an outer annular lip 28, and the flange 27 is provided with an outer annular lip 29, respectively received in annular rabbets 31, 32, at the outer faces of the respec-

tive ends of the annular elastic tube, to form annular extensions 33, 34, at the respective ends of said elastic tube received in the annular grooves within the annular lips 28, 29, formed by said lips.

70 The inner peripheral faces of the lips 28, 29, and the outer peripheral faces of the annular extensions 33, 34, are respectively of cylindrical form. The opposed ends of said lips and the end walls of the rabbets 31, 32, as well as the opposite ends of said extensions 33, 34, of the tube, and the bottoms of the annular grooves in which said extensions are received, are square with the axis of the cylinder, being located in planes parallel 75 with each other and perpendicular to said axis.

75 Direct endwise pressure is therefore exerted upon said flexible tube, in lines parallel with the axis of the press-head, by approach between the lower and upper sections of the press-head, the joints between the respective ends of said tube and said respective sections being continuously tight joints, so as to prevent the passage of the material being pressed, or juices thereof, or of the pressure fluid, past said joints into the interior of the press-head, these joints being tight throughout all conditions of movement 90 between the sections of the press-head, and whether said sections are in extended or approached relation, as will be seen from Figs. 2 and 3 of the drawing.

95 The lower section is provided with a recess 37, in which an enlargement 38 of the other section is arranged to be received. Means are provided for limiting the separating movement between the sections, shown accomplished by a bolt 41 threaded into the lower section and received through a bearing 42 in the upper section. The upper end of the bolt is located in a recess 43 in the upper section. A nut 44 is adjustably received in the recess over the bolt. Adjustment of the nut lengthwise of the bolt adjusts the extent of separating movement between the sections, as will be noted by comparison between Figs. 2 and 3. The upper end of the bolt and the nut have reciprocating movement in this recess.

100 Contact between the plastic material and the adjustable limiting means is avoided by providing a plug 45, having threaded engagement with the outer end of the wall of the recess 43. A gasket 46 is clamped by the plug against an annular shoulder 47 formed in the recess. The plug may be turned by a suitable square-ended wrench received in a hole 48 of square cross-section in the plate.

105 The lower section of the press-head is shown as of greater weight than the upper section, so as to insure a dropping of the lower section with relation to the upper section. The annular elastic tube 25 is re-

ceived about the inner wall of the rabbet 23, which forms the inner cylinder 24, and when the sections of the press-head are in separated relation, the elastic tube will be in 5 elongated relation in said rabbet, with the extensions 33, 34, of the elastic tube still securely held in the annular grooves in the opposed walls of said sections coating with said ends of said elastic tube, to maintain 10 a tight joint between the respective ends of said elastic tube and the respective end sections of the press-head.

The elastic tube will in this relation preferably be within the cylindrical projection 15 of the press-head, or compressive action thereon relieved, to permit ready sliding movement by the weight of the press-head between the outer periphery of said elastic tube and the inner surface of the cylinder.

20 This relation of parts is shown in Fig. 2, in which the press-head is shown in extended relation, corresponding to its descending movement, although when the parts are at their lowermost limit of movement, with the 25 lower section supported from the bottom of the cylinder, the weight of the upper section upon the elastic tube will have a spreading effect upon the tube to aid in preventing seepage of pressure past the press-head or 30 about the ends of the tube.

Plastic material having been placed in the cylinder above the press-head, and the cover 15 closed and clamped, pressure is supplied under the press-head through a suitable valve in a pipe 51, which latter communicates with the space under the press-head. The pressure acts against the lower face of the lower section of the press-head, raising this lower section, resisted by the 40 annular elastic tube, whereby the elastic tube is compressed in axial direction for reducing the length of said elastic tube and increasing its thickness, that is to say, its thickness and diameter are increased or spread outwardly, 45 its inner periphery being definitely positioned by the outer periphery of the inner cylinder 24, which is of unvarying diameter for maintaining the inside diameter of the elastic tube constant, and forcing the elastic 50 tube into intimate contact with the inner cylindrical face of the outer cylinder, to form a close slip-joint between the press-head and the wall of the cylinder, in order to avoid passage of the pressure fluid upwardly past the elastic tube or into the 55 press-head and passage of plastic material or its juices downwardly past the elastic tube or into the press-head.

The lateral spreading of the tube is caused 60 solely by the compressive action thereon in axial direction, causing intimate contact between the outer periphery of the tube and the inner periphery of the cylinder, but avoiding clamping or excessive pressure between the parts. It will be under-

stood further that as the press-head operates in the cylinder containing the meat-dough, the elastic tube is lubricated and seasoned by the juices of said meat-dough.

When the tube has thus been acted on by 70 the upward pressure on the lower section of the press-head sufficiently to support the upper section of the press-head and the weight of the plastic material thereabove, the press-head will move upwardly, with 75 the sections of the press-head in closer relation, and the elastic tube in spread relation, as indicated in Fig. 3. The upward movement of the press-head will force the plastic material through the nozzle. 80

When the upward movement of the press-head has been completed, and the pressure-valve is closed to shut off the supply of pressure and open the space in the cylinder under the press-head to the atmosphere, the 85 lower section of the press-head will drop with relation to the upper section thereof to the limit of separation permitted by the bolt 41 and nut 44, whereby the length of the elastic tube is again increased and its 90 diameter is again reduced to relieve the pressure of the elastic tube upon the inner surface of the cylinder, (see Fig. 2), for permitting descent of the press-head in the cylinder to follow the release of pressure in 95 said cylinder.

When the elastic tube is in compressed relation, it is securely held in lateral or radial directions between the outer cylindrical surface formed by the bottom of the outer annular rabbet in the press-head and the inner cylindrical surface of the cylinder, and between the top and bottom shoulders on the flanges of the sections of the press-head, and such holding relation is 100 maintained when the sections of the press-head are separated, for securely holding the elastic tube in position, forming close joints between the respective ends of said tube and the respective sections of the press-head, 105 and causing direct end-pressure by the flanges of said sections upon the ends of the elastic tube, to prevent shifting between said ends and said flanges, and to cause uniform lateral or radial spread of the body 110 of the elastic tube throughout its length. 115

The cover may then be again opened for recharging the casing with additional plastic material for repetition of the operation.

The elastic tube is preferably an integral structure and made of such composition, for instance with a rubber base, that the liquids in the meat dough or sausage filling and the cleaning operations will not crack or harden the same, experience having demonstrated that with my improved construction the elastic tube retains its life and is effective in operation for a very extended period of time. 120

Having thus fully described my inven- 125 130

tion, what I claim as new, and desire to secure by Letters Patent, is:

A press-head comprising an upper section and a lower section having cylindrical outer peripheries and relative movements in axial directions between them, one of said sections having an outer cylindrical rabbet forming an inner cylindrical wall, the other of said sections having a cylindrical flange received in said cylindrical rabbet about one end of said inner cylindrical wall, the end wall of said rabbet and the end of said flange each having a cylindrical lip at its outer periphery, said cylindrical lips projecting toward each other and forming cylindrical grooves within the same, and a cylindrical elastic tube, the respective ends of which are provided with oppositely extending cylindrical lips at their inner edges forming cylindrical grooves outside said lips, said lips on said sections and tube respectively maintained in said grooves in said tube and sections respectively, the bot-

toms of said cylindrical grooves and the ends of said cylindrical lips having end contact faces which are perpendicular to the axis of said press-head whereby direct end pressures are exerted upon said elastic tube in lines parallel with the axis of said press-head upon approach between said sections to compress said cylindrical elastic tube to increase its thickness and outside diameter, and to relieve said pressures and decrease the thickness and outside diameter of said elastic tube upon separation between said sections while maintaining the diameter of the inner periphery of said tube constant.

In testimony whereof, I have hereunto signed my name in the presence of two subscribing witnesses.

OSCAR C. SCHMIDT.
